DISPENSING CONTAINER FOR MUSTARD,
KETCHUP, AND THE LIKE, HAVING A
SLIDABLE PISTON WITH HOLLOW STEM

John Schwarz, Los Angeles, Calif.

Application September 19, 1950, Serial No. 185,538

1 Claim. (Cl. 222—320)

1

The present invention relates to containers of mustard, ketchup and the like. More particularly the present invention relates to dispensers for use in connection with containers of the type referred to.

It is an object of this invention to provide a dispenser for mustard, ketchup and the like, that is of simple construction, dependable in operation and easy to manipulate.

Another object of the invention is to provide a dispenser, of the type referred to, that is easy to clean.

Still another object of the invention is to provide a dispenser, of the type referred to, that may conveniently be held in and operated with one hand only.

Furthermore, it is an object of my invention to provide a dispenser, of the type referred to, that may conveniently be operated to dispense exactly the desired quantity of its contents.

These and other objects of my invention will be apparent from the following description of the accompanying drawings which illustrate a preferred embodiment thereof and wherein

Figure 1 is a vertical section through a mustard dispenser embodying my invention exposing the actuating mechanism within,

Figure 2 is another vertical section through the dispenser taken at right angles to the section illustrated in Figure 1, with the actuating mechanism in a different operational position.

The dispenser illustrated in Figures 1 and 2 comprises a cylindrical vessel 10 which may be of glass, plastic, metal or any other suitable material. The open upper end of said vessel is closed by a detachable lid structure 11, which is composed of a horizontal floor plate 12 from which rises an outer shell 13 of dome shape, the bottom edge of which is formed into a vertically depending annular lip 14 that fits telescopically over the upper end of the vessel 10. Slideably disposed within the vessel 10 is a centrally apertured piston or plunger 15 provided along its periphery with a suitable gasket 16 and secured to the lower end of a vertically rising tubular stem or piston rod 17. Said stem extends through, and is guided for vertical sliding movement by, an opening 19 in the plate 12 and an opening 20 in the crest of the dome shaped shell 13, with its projecting upper end suitably contracted, as shown at 21, to form a discharge spout 22 that may be closed by a cap 23 whenever the dispenser is not in use (Figure 1).

In practical use the vessel 10 is filled with mustard, ketchup or the like, below the plunger, as

2

indicated at 24 in both Figures 1 and 2, and by depressing the plunger the mustard in the vessel is forced upwards through the tubular stem 17 and discharges through the spout 22 at the upper end thereof. To operate the plunger the stem 17 is provided with a vertical rack bar 25 which extends along its outer surface through suitable notches 19' and 20' in the edges of the apertures 19 and 20, respectively (Figure 2). Said rack 25 is engaged by a gear 27 of small diameter which is secured to a horizontal shaft 28 that is rotatably supported by a pair of L-shaped brackets 29 and 30 which are bolted to and rise from the floor plate 12. To the left of the gear 27, as viewed in Figure 1, the shaft 28 carries another gear 32 of somewhat larger diameter which meshes with a third gear 33. Said third gear 33 is preferably of a smaller diameter than the gear 32 and is firmly mounted upon another horizontal shaft 34 that is rotatably supported in the brackets 29 and 30 above and parallel to shaft 28. Firmly mounted upon said last mentioned shaft is a manipulating wheel 35 which is of such diameter as to protrude partially through an arcuate slot 37 provided in the side of the dome shaped shell 13 of lid structure 11, as best shown in Figure 2.

To dispense mustard, ketchup or whatever the contents of the dispenser might be, a user merely grips the cylindrical vessel with one of his hands and moves the protruding segment of the manipulating wheel 35 with his thumb, which actuates the plunger 15. By virtue of the described transmission arrangement 27—32—33—35 rotation of the protruding wheel segment moves the plunger in the same direction in which said protruding wheel segment is moved. In other words, by turning the exposed wheel segment in downward direction, the plunger 15 is moved deeper into the vessel 10 extruding mustard through the spout 22 at the end of the tubular stem 17. Thus, in order to dispense the contents of the vessel 10 the user merely moves the exposed wheel segment toward himself, which is the convenient thing to do with the thumb of the hand that holds the vessel; and by virtue of the described relation in the size of the manipulating wheel 35 and the gears interposed between said wheel and the rack 25, rotation of the manipulating wheel 35 over an arc of the size exposed through the slot 37 may be arranged to advance the plunger 15 in small increments only so that there is no danger for excessive amounts of the contents of the vessel to be accidentally

dispensed when the described mechanism is operated.

As another advantage it should be noted that in the described dispenser construction neither the gear train nor the rack will ever come into contact with the contents of the vessel ¹⁰ so that the dispenser of the invention is easy to clean.

While I have described my invention with the aid of a particular embodiment thereof it will be understood that I do not wish to be limited to the specific constructional details illustrated and described, which may be departed from without departing from the scope and spirit of my invention.

I claim:

A dispenser for mustard, ketchup and the like, comprising a vessel having an open upper end, a lid structure arranged to close said vessel and composed of a horizontal floor plate and an outer shell of dome shape, said shell having an opening in its crest and an arcuate slot within its side wall extending within a vertical plane and said floor plate having a central opening in vertical alignment with the opening in the crest of said shell, a tubular stem extending slideably through said openings from above said shell into the interior of said vessel, a centrally apertured plunger secured to the lower end of said stem

within said vessel, a rack provided on said stem and extending over the major portion of its length, a gear in mesh with said rack rotatably supported from and within said lid structure, a manipulating wheel rotatably supported by and within said lid structure and arranged to protrude partially through the lateral slot of said shell thereof, and a gear train interposed between said manipulating wheel and said first gear to effect co-directional movement of said plunger and the exposed segment of said wheel whenever said wheel is manipulated.

JOHN SCHWARZ.
